UNITED STATES PATENT OFFICE.

SIMON CLARY, OF CARNEGIE, PENNSYLVANIA.

RAILWAY-SWITCH.

SPECIFICATION forming part of Letters Patent No. 793,990, dated July 4, 1905.

Application filed September 16, 1904. Serial No. 224,676.

To all whom it may concern:

Be it known that I, SIMON CLARY, a citizen of the United States of America, residing at Carnegie, in the county of Allegheny and State of Pennsylvania, have invented certain new and useful Improvements in Railway-Switches, of which the following is a specification, reference being had therein to the accompanying drawings.

10 This invention has relation to switch-rails, and has for its object to provide a novel form of switch-rail, wherein the same can be manufactured at a comparatively small expense and operated with considerable ease.

15 The invention as contemplated by me aims to provide a switch rail or tongue, which may be formed of a T-rail, it having been heretofore necessary to machine the T-rails in order to permit of the proper positioning of the 20 same in relation to a rail.

In forming my improved switch rail or tongue I have provided novel means whereby a rail can be used without machining the base of the same, and in order to accomplish this 25 I have employed a rail-plate and a novel form of rail, whereby the T-rail may be correctly positioned in respect to a rail.

With the above and other objects in view the invention consists in the novel construction, combination, and arrangement of parts 30 to be hereinafter more fully described and specifically pointed out in the claims.

In describing the invention in detail reference is had to the accompanying drawings, 35 forming a part of this application, and wherein like numerals of reference indicate like parts throughout the several views, in which—

Figure 1 is an end view of my improved 40 switch-rail, showing the same in position upon a tie and its relative position to a rail. Fig. 2 is a top plan view of a switch, showing my improved switch-rail in position. Fig. 3 is a fragmentary perspective view of the 45 switch-rail. Fig. 4 is a perspective view of the rail-plate employed in connection with the switch-rails. Fig. 5 is a detail perspective view of a portion of a rail used in connection with my improved switch-rail.

Heretofore where switch rails or tongues 50 have been employed it has been necessary to machine the T-rail in order that when the switch rail or tongue is installed that such rail or tongue may be properly positioned in respect to a rail, and the T-rails have been 55 machined to permit of the movement of said T-rail over the base of the rail, this machining of the T-rails being a considerably expensive and troublesome feature in the manufacture of switch rails or tongues, and my invention contemplates providing a switch rail or tongue whereby this inconvenience is dispensed with. In order to dispense with the machining of these T-rails, I employ a rail-plate 1, which is clearly illustrated in Fig. 4 60 of the drawings, this rail-plate being of a sufficient length to form a seat for the track-rail and a guide-plate for the switch rail or tongue. The rail-plate is provided with a cut-away portion 2, forming a seat for a 70 track-rail 3, and the ends of said plate are provided with apertures 4 4, whereby the same may be spiked or otherwise secured to the ties 5. The sections of the track-rails which are employed adjacent to my im- 75 proved switch rails or tongues have the base portion 7 on one side of the rail on a plane below the portion 6 of the base on the opposite side of the rail, this lowered flange of the base portion of the rail extending the en- 80 tire distance along the rail to permit of the movement of the switch rail or tongue toward or against the rail-section 3. As illustrated in Fig. 2 of the drawings, this lowered flange of the base portion of the rail ex- 85 tends approximately the distance of one tie to the other; but the same may vary according to the contact-surface of the switch rail or tongue with the rail 3.

In constructing a railroad the plates 1 are 90 secured upon the ties and the rail-sections 3 secured upon said plates by the ordinary type of rail fastener and support 8, and in placing the rail-sections upon said plate the lowered flange portion 7 of each rail is placed 95 in the seat 2, whereby the top surface of this lowered flange portion 7 will be horizontally aligned with the top of the plate 1 and a

smooth surface provided for the movement of the switch tongue or rail, which will now be described. This switch rail or tongue is formed of an angular T-rail 9, the vertical portion of which is provided with a tapering edge 10, whereby the same may be moved into close proximity to the rail-section 3. This switch-rail is provided near its end with a plate 11, that is provided with lugs 12 12, 10 this plate being secured to the switch-rail by any desired means, bolts and nuts being commonly employed. In the lugs 12 12 a switch-rod 14 is secured, this rod passing under the base portions of the opposite rails, as clearly 15 illustrated in Fig. 2 of the drawings.

It will thus be seen from the foregoing description, taken in connection with the accompanying drawings, that the machining of the switch-rails or T-rails is entirely dispensed with and that a smooth and plain surface is provided for the path of travel of the said switch rail or tongue, and while I have herein shown the plates 1 as being made of separate castings I wish it to be understood that if it be so desired these plates may be made of a considerable length in order to support one or more switch-rails, and other changes may be made without departing from the general spirit and scope of my 30 invention.

Having fully described my invention, what I claim as new, and desire to secure by Letters Patent, is—

1. The combination with a rail, said rail having a portion of one side of its base countersunk, of a plate, said plate having a seat formed therein for the reception of said countersunk portion of the rail, a switch-rail formed of a T-rail, and means for operating said switch-rail upon said plate and said countersunk portion of the rail, substantially as described.

2. The combination with a rail, said rail having a portion of its base countersunk, means for supporting said rail upon a tie, a switch-rail, and means for operating said switch-rail in relation to the main rail.

3. A rail having a tread and web of T shape in cross-section, and having a base consisting of flanges projecting from opposite sides of the web, the base-flange on one side being on a plane below the base-flange on the other side.

4. A rail comprising a tread and web of T shape in cross-section, and having base-flanges projecting from the web in different planes, said tread being beveled on one side at one end of the rail.

5. In a switch, the combination of a rail, the inwardly-extending base-flange of said rail extending below the outwardly-extending base-flange, and a switch-rail moving upon said inwardly-extending flange.

6. In a switch, the combination of a rail having a seat formed upon one of its flanges, and a switch-rail slidingly secured upon said seat, substantially as described.

7. In a switch, the combination of a rail having one of its base-flanges extending on a different plane than the other base-flange, and a movable switch-rail slidingly secured upon the lower base-flange, substantially as described.

8. In a switch, the combination of a rail, having a base-flange projecting outwardly from both sides of the rail-web, the portion of the base-flange projecting from one side of the rail-web being on a plane below that of the portion of the base-flange projecting from the opposite side of the rail-web, and a switch-rail mounted to slide on the lower portion of the base-flange.

9. In a switch, the combination of a rail having a base-flange arranged at right angles to the web portion of the rail on a plane below the base portion of the rail on the opposite side of said web, and a sliding switch-rail mounted on the lowermost base portion of the rail, substantially as described.

10. In a switch, a rail having a tread and web of T shape in cross-section, and having the upper face of the base-flange on one side of the rail on the same plane as the underneath face of the base-flange on the opposite side of the rail, as and for the purpose described.

11. A rail having a tread and web of T shape in cross-section and provided with a base-flange on one side having its upper and lower faces in parallel planes.

12. In a switch, the combination with a T-rail, of a rail-plate having a seat to receive the base-flange on one side of the rail-web and bring the upper face of said base-flange in a plane with the upper face of the rail-plate.

13. In a switch, the combination with a rail having the base-flanges on opposite sides in different planes, of a rail-plate on which the uppermost base-flange of the rail rests and which has a seat to receive the lowermost base-flange of the rail and bring the upper face of said lowermost base-flange in the same plane as the upper face of the rail-plate.

14. In combination with a rail-plate having a seat, a rail having its base-flange on one side received in said seat with its upper face in plane with the upper face of the rail-plate.

In testimony whereof I affix my signature in the presence of two witnesses.

SIMON CLARY.
